US0D1076888S

(12) **United States Design Patent** (10) **Patent No.:** **US D1,076,888 S**
(45) **Date of Patent:** **** May 27, 2025**

(54) **WIRELESS MICROPHONE**

(71) Applicant: **Maocai Huang**, Yunnan (CN)

(72) Inventor: **Maocai Huang**, Yunnan (CN)

(**) Term: **15 Years**

(21) Appl. No.: **29/866,627**

(22) Filed: **Sep. 21, 2022**

(51) **LOC (15) Cl.** **14-01**

(52) **U.S. Cl.**

USPC **D14/226**; D14/228; D14/497

(57) **CLAIM**

The ornamental design for a wireless microphone, as shown and described.

DESCRIPTION

FIG. 1 is a perspective view of a wireless microphone showing my new design;

FIG. 2 is another perspective view thereof;

FIG. 3 is a front view thereof;

FIG. 4 is a back view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion of FIG. 8; and,

FIG. 10 is an enlarged view of portion of FIG. 1.

The broken lines in the drawings depict portions of the wireless microphone that form no part of the claimed design. The dot dash broken lines encircling portions of the wireless microphone in FIGS. 1 and 8, and illustrated in the enlarged view of FIGS. 10 and 9, form no part of the claimed design.

1 Claim, 10 Drawing Sheets
